UNITED STATES PATENT OFFICE

138,059

DESIGN FOR A COMBINED ASH TRAY AND STATUETTE

Ronald K. Pohl, White Plains, N. Y.

Application February 29, 1944, Serial No. 112,745

Term of patent 7 years

(Cl. D85—2)

To all whom it may concern:

Be it known that I, Ronald K. Pohl, a citizen of the United States, residing in the city of White Plains, county of Westchester, and State of New York, have invented a new, original, and ornamental Design for a Combined Ash Tray and Statuette, of which the following is a specification, reference being had to the accompanying drawing, forming a part thereof, in which:

The figure is a perspective view of a combined ash tray and statuette showing my new design.

I claim:

The ornamental design for a combined ash tray and statuette, as shown.

RONALD K. POHL.
